(57) **CLAIM**

The ornamental design for a display package, as shown and described.

DESCRIPTION

FIG. 1 is a front, right perspective view of a display package showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top side elevation view thereof; and,

FIG. 7 is a bottom side elevation view thereof.

The broken lines showing are for illustrative purposes and form no part of the claimed design.
